UNITED STATES PATENT OFFICE.

ABRAHAM C. BAKER AND JOHN VAN DYNE, OF HYDE PARK, NEW YORK.

IMPROVEMENT IN CAR-COUPINGS.

Specification forming part of Letters Patent No. 36,331, dated September 2, 1862.

To all whom it may concern:

Be it known that we, ABRAHAM C. BAKER and JOHN VAN DYNE, both of Hyde Park, in the county of Dutchess and State of New York, have invented a new and Improved Car-Coupling; and we do hereby declare that the following is a full, clear, and exact description of the same, reference being had to the accompanying drawings, making a part of this specification, in which—

Figure 1 is a side sectional view of our invention, taken in the line *xx*, Fig. 2; Fig. 2, a horizontal section of the same, taken in the line *yy*, Fig. 1; Fig. 3, a vertical section of the same, taken in the line *zz*, Fig. 1.

Similar letters of reference indicate corresponding parts in the several figures.

The object of this invention is to obtain a car-coupling which will be self engaging or connecting and admit of being readily disconnected by the foot of the operator or brakeman on the platform of either of the two cars which the coupling connects, the parts being so arranged that the shackle of the coupling will always be retained in a horizontal position, or nearly so, in the draw-head, so as to insure its entrance into the draw-head of the car which is not provided with the shackle.

The invention consists in the employment or use in the draw-head of a car of two jaws acted upon by springs and having guides arranged relatively with them, and also levers and a foot-frame, as hereinafter fully shown and described, whereby the desired end is attained.

To enable those skilled in the art to fully understand and construct our invention, we will proceed to describe it.

A represents the draw-head of a car, which is of rectangular form, and is connected with an elastic or yielding bar under the car-body, as usual, so as to form a buffer. The draw-head may be of cast or wrought iron, and within these are placed two jaws, *B B*, which are formed of metal plates secured at their back ends in the draw-head on axes or journals *a*, and having projections *b* at the inner sides of their outer ends to form hooks, as shown clearly in Fig. 1.

C C C represents springs, which bear against the outer surfaces of the jaws *B B*, and have a tendency to keep their outer ends toward each other and to keep transverse bars *D*, which

are attached to the jaws *B*, in contact with levers *E E*, which are on a shaft, *F*, fitted horizontally in the draw-head *A* between the two jaws. The levers *E E* are near the ends of the shaft *F*, a lever being at each side of the jaws, and the ends of the bars *D* project sufficiently beyond the sides of the jaws, so that they may be in contact with the levers *E E*. (See Fig. 3.)

The ends of the shaft *F* extend through the side of the draw-head and have each an arm, *G*, attached to them. These arms extend upward above the draw-head, and are connected by a cross-bar, *H*. (See more particularly Fig. 3.)

I I represent two guides, which are attached one to the upper and the other to the lower plate of the draw-head. These guides, when the jaws *B B* are distended, pass through slots *c c* in the jaws.

J is a shackle, which is formed of a straight bar, *d*, having a *V*-shaped head, *e*, at each end. The back ends of the heads *e* project sufficiently out from the bar *d* of the shackle to form shoulders *f f*, as shown in Fig. 1, and when the shackle is forced into the draw-head the head *e* of the shackle will force apart the jaws *B B* and pass between the guides *I I*, the projections *b b* of the jaws *B B* being forced down behind the shoulders *f f* of the head *e* of the shackle as soon as said shoulders pass behind the projections *b b*.

The guides *I I* serve as bearings for the head *e* of the shackle and keep it in a horizontal position when not supported at its outer end, thereby enabling the shackle to enter the draw-head of an approaching car; and in order to prevent the shackle *J* being forced back within the draw-head *A* when entering between the jaws of an approaching draw-head, a stop, *K*, is used for the end of the shackle to bear against, said stop being simply a cross-bar fitted in the draw-head. (See Figs. 1 and 2.)

Thus it will be seen that the device is self-coupling, a person not being required to pass between the platform of two cars in order to connect them. The pull of the shackle is on the jaws *B B*, and in order to disconnect the shackle the operator or brakeman forces outward the arms *G G* by pressing his foot against the cross-bar *H* thereof, and by so doing turns the shaft *F* and levers *E E*, which act simultaneously against the bars *D* of the jaws *B B* and cause the latter to be forced apart, so as to release the shackle.

The coupling is exceedingly simple and effi-

cient and possesses the advantage of not requiring the attendant or brakeman to leave the platform to couple and disconnect, and at the same time the coupling may be disconnected in a moment by any person within a car by simply stepping on the platform and shoving forward the arms G G, the cross-bar H of which is just in front of the platform and a trifle above it.

We do not claim the yielding or elastic jaws B B, for they have been previously used; but

We do claim as new and desire to secure by Letters Patent—

The yielding jaws B B, with the transverse

bars D D attached, in combination with the shackle J and levers E E, the latter being placed on the shaft F, which is provided with the arms G G, connected by the cross-bar H, the above parts being used with or without the guides I I, and fitted in or applied to the draw-head A, as and for the purpose set forth.

ABRAHAM C. BAKER.
JOHN VAN DYNE.
